EXPANSIBLE LINK CHAIN FOR A BRACELET OR THE LIKE

Emil Rodriguez, New York, N. Y., assignor to
Jacoby-Bender, Inc., New York, N. Y., a corporation of New York

Application November 22, 1952, Serial No. 22,408

Term of patent 7 years

(Cl. D45—4)

To all whom it may concern:

Be it known that I, Emil Rodriguez, a citizen of the United States, and a resident of New York, county and State of New York, have invented a new, original, and ornamental Design, for an Expansible Link Chain for a Bracelet or the like, of which the following is a specification, reference being had to the accompanying drawing forming a part thereof, in which:

Fig. 1 is a top plan view of the expansible link chain in contracted condition showing my new design, the conventional bottom links being shown in broken lines;

Fig. 2 is a top plan view thereof in partially expanded condition, portions of the conventional bottom links being visible between the top links and shown in broken lines;

Fig. 3 is a top plan view, on an enlarged scale, of one of the top links of the chain of Fig. 1;

Fig. 4 is an end elevational view of the link of Fig. 3; and

Fig. 5 is a side elevational view thereof taken from the right hand side of Fig. 3.

I claim:

The ornamental design for an expansible link chain for a bracelet or the like, as shown.

EMIL RODRIGUEZ.
